PICKER STICK CHECK STRAPS

Harold J. Johnson, Denver, Colo., assignor to The Gates Rubber Company, Denver, Colo., a corporation of Colorado

Application February 23, 1946, Serial No. 649,521

1 Claim. (Cl. 139—165)

1

This invention relates to improvements in picker stick check straps.

In the textile industry, the looms usually employed are provided with oscillating picker sticks and pickers, for operating the shuttle. Such pickers are oscillated at a very high speed and since they have considerable mass, a high momentum is developed and severe shocks therefore result if the picker stick is brought to a sudden stop.

For the purpose of checking the movement of the picker sticks and bringing them to a shockless stop at the end of each stroke, various devices have been invented.

It is the object of this invention to produce a simple and substantial check mechanism that will permit free movement of the picker sticks during the greater part of their stroke and which will subject them to retarding forces that increase gradually towards the ends of the stroke.

Another object of this invention is to produce a device of the class described in which the retarding mechanism is formed from a number of belts, preferably of the V-type which are mounted on the loom by means of a simple snubbing mechanism, and which therefore can be applied to existing looms without any material change in the construction.

Another object of this invention is to produce a device of the class described in which any degree of checking action desired can be obtained, to best suit the peculiarities of the loom to which it is applied.

A further object of the invention is to produce a simple attaching means that produces a snubbing action which determines the forces required to move the belts and which can be adjusted to vary this force for the purpose of suiting it to the operation of the picker sticks.

Another object is to produce mechanism that will continue to function if one of the belts should break and in which a broken or worn out belt can easily be replaced.

Having thus briefly described the invention and the objects thereof, the invention will now be described in greater detail and for this purpose reference will be had to the accompanying drawing in which the invention has been illustrated in its preferred form, and in which:

Figure 1 is a side elevation showing a portion of the loom, the upper part of the picker stick and the check mechanism;

Figure 2 is a side elevation similar to that shown in Figure 1, but shows the picker stick at the opposite end of its stroke;

2

Figure 3 is a plan view looking through plane 3—3, Figure 1, the upper end of the picker stick being shown in section;

Figure 4 is a section taken on line 4—4, Figure 2;

Figure 5 is a diagrammatic side elevation showing a slight modification;

Figure 6 is a view similar to that shown in Figure 1, showing a slightly different modification; and

Figure 7 is a fragmentary detail showing the lower end of a snubber pin.

In the drawing reference numeral 10 designates the shuttle support or table and reference numeral 11 the picker stick. A picker 12 has been shown as secured to the top of the picker stick.

Attached to the under side of the table 10 are two snubber assemblies, each comprising a base 13 having two downwardly extending spaced snubber pins 14. The base is provided with an outwardly extending lug 15 having a notch 16 in which is secured an adjustable snubber pin 17. Snubber pins 14 and 17 are arranged as shown in Figure 4 and since snubber pin 17 is adjustable transversely, the curvature of the belts 18 can be varied by varying the relative position of the snubber pins. The picker stick passes through the belts in the manner shown in Figures 3 and 4.

Picker sticks employed in loom mechanism of the type here referred to moves about a pivot of such a construction that the picker 12 has a substantially straight line motion. The result of this is that at opposite ends of its stroke, the picker stick is inclined with respect to the vertical, but in opposite directions.

In the construction illustrated in Figures 1 to 4, belts 18 are of the same length and therefore when the picker stick is in the position shown in Figure 1, the belts are offset from each other so that the picker stick at the end of each stroke will be in contact with all of them. When the picker stick begins its movement towards the position shown in Figure 2, it separates from the belts and moves freely until it engages the inner surface of the upper belt in the assembly. Any further movement first elongates the belt loop and then slides the belt in the snubber until the picker stick comes into contact with the next belt below, whereupon the two upper belts slide, allowing the picker stick to come into engagement with the third belt from the top and this continues until the picker stick is in engagement with all of the belts in the assembly.

Any further movement of the picker stick now requires all of the belts to slide in the snubber until the picker stick reaches the extreme position shown in Figure 2. On the return motion the snubbing action is repeated, but in the opposite direction, bringing the belts back to the position shown in Figure 1.

Since the belts have a tendency to assume a circular shape, the first checking action begins when the picker stick engages the inner surface of the upper belt and bends it towards the shape shown in Figure 4. During this bending operation, the picker stick engages one or more of the belts positioned underneath which are correspondingly changed in shape. When the force becomes strong enough, the belts begin to slide in the snubber.

As above stated, Figures 1 to 4 show belts of the same size and length. However, it is permissible to employ belts of different lengths and to arrange them with the longest belt on top as shown in Figure 5, or with the shortest belt on top, as shown in Figure 6. Different check actions may be obtained by this variation in the lengths of the belts. With the arrangement shown in Figure 6, it is evident that the upper belt must slide farther than those below to a greater extent than with the arrangement having belts of equal length, and conversely, if the upper belts are the longer the movement of the upper belt will be less in proportion than with the arrangement shown in Figure 6.

By moving snubber pin 11 inwardly or outwardly, resistance offered to the sliding of the belts can be increased or decreased until the best operation is obtained. The lower ends of the snubber pins are provided with lateral projections 19 as shown in Figure 7 and these serve to prevent the belts from falling from the snubber.

From the above description it will be apparent that the picker stick check mechanism that has been shown and described opposes a gradual and increasing force to the picker stick, thereby gradually bringing it to a stop. This check mechanism, by decreasing the shock due to the quick stopping of the picker stick, increases the life of the mechanism and results in a smoother and more uniform operation.

The belts employed have a long life for the reason that they are subjected to comparatively little wearing force in sliding past the snubber pins, as the surfaces of the latter are always

smooth and polished and due to the number of belts employed, the force exerted by each can be comparatively small because the retarding forces are accumulative and the total therefore depends upon the number of belts which can be increased or decreased as desired.

If the belts are not of the endless type and require a splice, this is preferably positioned so that it will not have to pass through the snubber. In most instances, however, endless belts can be employed, but spliced belts may be used if desired. The belts may be round, V-shaped or flat, but should all have the same cross sections. It is evident that the breakage of any one belt does not render the device inoperative. A broken belt can be readily replaced when the loom is idle.

Throughout the specification and claims, the terms "belt" and "belts" have been used. It is, of course, evident that straps designed specifically for this purpose may be used. Straps of ordinary belt construction are, however, well suited for this purpose.

Having described the invention, what is claimed as new is:

25 A picker stick check device comprising a plurality of separate, endless straps arranged in the form of a loop, encircling the picker stick, the several strap loops being independent throughout their entire lengths and mounted for independent movement, in edge contacting relation, forming a check strap loop whose width is equal to the combined width of the several straps, and friction snubbers on both sides of the loop, operatively associated therewith to resist longitudinal movement, the length of the loops being less than the travel of the picker stick stroke at that point, whereby each strap will move different distances and produce a snubbing effect that increases as 30 the picker stick approaches the end of its stroke.
